UNITED STATES PATENT OFFICE.

CHARLES WESLEY DAWSON, OF DAYTON, OHIO, ASSIGNOR TO DAYTON SCALE COMPANY, OF DAYTON, OHIO, A CORPORATION OF NEW JERSEY.

CLAMP IN MEAT-SLICING MACHINES.

Application filed June 3, 1924. Serial No. 717,467.

To all whom it may concern:

Be it known that I, CHARLES WESLEY DAWSON, a citizen of the United States of America, residing at Dayton, in the county of Montgomery and State of Ohio, have invented certain new and useful Improvements in Clamps in Meat-Slicing Machines, of which the following is a full, clear, and exact description.

10 This invention relates to improvements in clamping devices for use in connection with meat slicing machines and more particularly is directed to the provision of a supplementary clamping device which is 15 adapted for attachment to the regular clamp in order that sausages, bologna or the like may be secured in position for cutting. The attachment is arranged so that it can readily be placed in position or removed 20 so that the slicing machine can be operated for regular slicing or special slicing without the necessity of changing and replacing the relatively heavy and cumbersome main clamp.

25 A further object of this invention resides in the provision of a clamping attachment which can be adjusted angularly to permit diagonal slices to be cut from bologna, sausage or the like.

Other objects and advantages will be hereinafter pointed out in the accompanying specification and claims and shown in the drawings which show a preferred embodiment of the invention.

35 In the drawings,

Fig. 1 shows the clamping attachment in position upon the main clamp of a slicing machine.

Fig. 2 shows an enlarged view of the 40 attachment removed from the main clamp.

Fig. 3 shows the parts adjusted for diagonal slicing.

Fig. 4 is a detail sectional view taken on line 4-4 of Fig. 1.

45 In the drawings, 10 represents the usual meat tray or plate which is provided with tines 11 and which has secured thereto the usual posts 12. The main clamp is slidably guided upon these posts and includes a central boss portion 13 through which extends a horizontal shaft 14 which actuates the adjusting pinions 15. The main clamp forms the subject matter of application of George R. Wood, Serial No. 659,029, filed 50 August 24, 1923.

The supplementary clamp comprises a plate 16 having a pair of arms 17 extending upwardly therefrom and provided with curved lug portions 18 at the top thereof adapted to fit over the cross shaft 14 at the sides of boss 13. When the supplementary clamp is placed in position suitable posts 19 on the plate abut against the bottom of the central lug portion and prevent the tipping of the supplementary clamp in a 60 anticlockwise direction (see Fig. 1). To retain the supplemental clamp in position and to prevent clockwise rocking movement I provide a spring catch 20 fixed to plate 16 and having a lug 21 adapted to engage behind the edge of the cover plate 22 on the boss 13.

The clamping tines 23 of the supplementary clamp are disposed arcuately as shown in Fig. 2 and are preferably but not necessarily struck up from a bent plate 24 which is pivoted at 25 on plate 16. A suitable handle 26 is fixed to the plate 24 and is provided with a shouldered stud which is adapted to slide back and forth in an arcuate slot 27 in the plate 16. It will be apparent that the pivoted plate construction permits the clamping tines to be adjusted to any desired angle within the limits determined by the slot 27 thus permitting 80 pieces of bologna, sausage or the like to be clamped for diagonal slicing.

It will be understood that the tines 23 may be provided directly upon the plate 16 if the adjustable feature is not desired.

90 In the use of slicing machines the user can be provided with a number of clamping devices of different sizes, some of which may be of the adjustable type. The user can then select the proper size clamp and apply it to the main clamp. The supplementary clamp may be readily removed by depressing the spring catch 20 and tipping the parts until the posts 19 are clear of the boss 13.

100 What I claim is—

1. In a slicing machine having a main meat clamp, in combination with a supplementary clamp adapted for attachment and removal to and from the main clamp, said supplemental clamp having arcuately disposed tines to permit the clamping devices to grip circular bologna and the like.

110 2. In a slicing machine having a main clamp, in combination with a supplemental

- 2
- clamp, adapted for attachment thereto to permit the clamping of sausage and the like, a tined portion on said supplementary clamp and means for angularly shifting 5 said tined portion relatively to the other parts of the supplementary clamp to permit diagonal slicing of articles gripped by the supplemental clamp.
3. A supplemental clamp adapted for attachment to the main clamp, of a slicing machine, said supplemental clamp comprising a base plate, a pair of supporting arms connected to and extending upwardly therefrom for engaging parts of the main clamp, 10 and a tine section secured to said plate and having substantially arcuately disposed tines projecting downwardly therefrom for the purpose described.
4. The invention set forth in claim 3, in 15 which the tine section is pivotally adjustable with respect to the plate portion.
5. A supplementary clamp for attachment to the main clamp of a slicing machine to permit the gripping of relatively small 20 articles having a curved contour, said clamp comprising a main body portion, means connected thereto for removably supporting the said portion upon the main clamp, a downwardly extending tine portion connected to 25 said body portion for gripping the articles, and a releasable locking means for locking the supplemental clamp to said main clamp.
6. A supplemental clamp adapted for attachment to a main clamp of a slicing machine, said clamp comprising in combination with a main body portion, means in- 30
- cluding lugs adapted to engage parts of the main clamp to support the supplemental clamp thereby, means for preventing tilting of the supplemental clamp with respect 40 to the main clamp, and a depending portion connected to said main body portion and including a plurality of tines disposed in arcuate relation for the purpose de- 45 scribed.
7. A clamp adapted to be attached and removed to and from the parts of a slicing machine comprising a main plate, a pair of arms provided with engaging lugs connected to and extending from said plate, 50 a bent tine plate, pivotally connected to said first mentioned plate, a handle connected to said tine plate, a pair of post-like members extending from said main plate and a spring catch carried by main plate adapted 55 to engage the parts of the slicing machine to secure the clamp parts thereto.
8. A supplemental clamp for a slicing machine adapted for attachment and removal to and from the main clamp there- 60 of, said supplemental clamp comprising means pivotally engaging parts of the main clamp for supporting the supplemental clamp thereby, means for preventing tilting movements of said supplemental clamp means for locking the supplemental clamp upon said main clamp and means upon said supplemental clamp for gripping curved 65 pieces of meat.

In testimony whereof I hereto affix my 70 signature.

CHARLES WESLEY DAWSON.
